J. M. PUN.
PORTABLE REFRIGERATOR.
APPLICATION FILED MAY 15, 1920.

Patented May 3, 1921.

INVENTOR.
Jack M. Pun
BY *George J. Weller* ATTORNEY

UNITED STATES PATENT OFFICE.

JACK M. PUN, OF STOCKTON, CALIFORNIA.

PORTABLE REFRIGERATOR.

1,376,577.

Specification of Letters Patent.

Patented May 3, 1921.

Application filed May 15, 1920. Serial No. 381,559.

To all whom it may concern:

Be it known that I, JACK M. PUN, a citizen of the United States, residing at Stockton, in the county of San Joaquin, State of California, have invented certain new and useful Improvements in Portable Refrigerators; and I do declare the following to be a full, clear, and exact description of the same, reference being had to the accompanying drawings, and to the characters of reference marked thereon, which form a part of this application.

This invention relates to improvements in portable refrigerators such as are used for shipping perishable food-stuffs, and particularly to a type intended to carry dry-chilled products of all kinds, such as fowl, which it is not desirable shall come in contact with the ice, or the water therefrom, at any time.

The principal object of the invention is to devise a refrigerator for this purpose in which a maximum weight of produce may be carried with a minimum of weight of ice and refrigerator, and in which no ice or ice water can come in contact with the produce at any time.

Another object is to make an airtight refrigerator and to so construct the same that there will be no metal parts, which are good conductors of heat, extending from the exterior to the ice or produce chamber to transmit heat thereto which would be instrumental in causing the warming of the produce and melting of the ice.

A third object is to provide a refrigerator well adapted to withstand the hard usage incident to frequent loading and unloading from railroad cars, trucks, etc.

A further object of the invention is to produce a simple and inexpensive device, and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views.

Figure 1 is a perspective view of the exterior of the refrigerator.

Fig. 2 is a cross sectional view of the same.

55

Referring now more particularly to the characters of reference on the drawings, the numeral 1 denotes the exterior box or casing, preferably of wood, and lined with cork composition 2 or some similar light and non-heat conducting material, which projects above the top of the casing 1 all around the same for a suitable distance.

This leaves a shelf or ledge 3 around the casing to support a rubber gasket 4.

65

A cover 5, of similar construction to the casing 1, rests on the gasket.

Metal straps 6 pass around the outside of the casing and have formed therewith hinges 7 along the abutting line of one edge of the cover with the corresponding casing-shelf. Across the top of the cover these straps converge, having formed therewith at that point a slotted projection 6^a adapted to receive a pin 8 hinged to the converging straps 6 therebelow, such pin having a wing nut 9 threaded thereon and adapted to bear down on the portion 6^a.

75

By this means, a simple fastening is provided between the cover and the casing, while at the same time the casing is both strengthened and protected by the practically continuous metal straps. The catch members are so positioned relative to each other that when in engagement, the gasket 4 is firmly squeezed between the cover and the casing-shelf to exclude all air. Bolts or screws are used to secure the straps to the casing which do not extend through the cork lining 2.

90

In the interior of the casing is a metal receptacle 10, spaced from the sides of the casing to form air passageways 11, which communicate with the interior of the receptacle by means of a plurality of holes 12 in the sides thereof. The top of the receptacle laps over the top of the cork lining, and then bends down and terminates adjacent the shelf 3.

95

The gasket 4 is therefore preferably made of a lesser width than the shelf, so that it may be kept from contact with the metal, and so preventing any tendency of the rubber from transmitting any heat from the exterior to the metal of the receptacle.

105

The sides of said receptacle are held in

spaced alinement from the lining 2 by means of cleats 13 positioned at intervals therebetween, and secured either to the receptacle or to the cork.

5 A central well 14 is fixed to the bottom of the receptacle and projects upwardly a certain distance.

Resting on top of the well and also on cross-cleats 15 fixed to the receptacle 10, is 10 what may be termed a combination ice container and cover for said receptacle. This member 16 consists of a bottom 17 flaring upwardly and outwardly from the edges of the well to the sides of the receptacle. From 15 this point the sides 17^a of the container extend to the top of the receptacle parallel and adjacent to the sides thereof, and are then bent over somewhat and then bent down to a termination adjacent the angle of the 20 bottom with the sides as at 18, thus forming a triangular air chamber 19 all around the upper portion of the container. Holes 20 are cut through both walls of this air chamber at spaced intervals, the holes in 25 the outer wall being lower than those in the inner walls.

The bottom of the container extends down into the well 14 somewhat as at 21, and is spaced from the sides thereof to allow of a 30 flow of air from said well into the receptacle through holes 22 in the well positioned therein so as to be protected by the portion 21, so that ice or water can never run through said holes.

35 A drain pipe 23 leading to the exterior of the refrigerator is fitted in the bottom of the well.

The member 16 is removable from the refrigerator, and the receptacle 10 is likewise removable, the well 14 being permanently fixed therein.

To load the refrigerator, the member 16 is removed, and the produce to be shipped, preferably already chilled, is placed in the 40 receptacle 10 all around the well 14, and as high as the top of the same. The member 16 is then replaced, and it and the well 14 are then packed with ice prior to fastening down the main cover 5.

50 If this packing operation is properly carried out, it should not be necessary to re-ice the refrigerator even on a journey consuming several days, since the refrigerator is absolutely air-tight except for the drain- 55 pipe at the bottom, which on account of its position, will not take any warm air therein.

The air inclosed in the refrigerator can of course readily circulate from the receptacle to the ice container and vice versa 60 through the various sets of holes 12, 20 and 22.

It is of course understood that the well 14 has watertight connection with the bottom of the receptacle, so that no ice water 65 can pass from one to the other.

By reason of the centrally positioned well, the ice is directly in the middle of the produce, and is removed from possible heating influences from without.

In order to positively prevent any water 70 from possibly entering the produce-compartment through the holes 21, in the event that the ice in the chamber 14 has solidified into a solid mass and prevents the water from the top ice from issuing through the 75 hole 23, I place small discharge pipes 24 in opposite corners of the well 14 leading to the pipe 23, the upper ends of said pipes passing between the flange 21 and the side 80 of the well, and terminating slightly below the holes 22. Thus any water accumulating at this level, will be drained out through the bottom, and regardless of whether the refrigerator as a whole is perfectly horizontal or not.

85

From the foregoing description it will be readily seen that I have produced such a device as substantially fulfills the object of the invention as set forth herein.

While this specification sets forth in detail the present and preferred construction of the device still in practice such deviations from such detail may be resorted to as do not form a departure from the spirit of the invention, as defined by the appended 95 claims.

Having thus described my invention what I claim as new and useful and desire to secure by Letters Patent is:—

1. A refrigerator comprising a receptacle 100 to receive the produce, a water tight ice well in the receptacle, a removable combined cover and ice retainer fitted in the receptacle above the well and in communication therewith, the bottom of the well having a drain outlet, and a small pipe leading from a point substantially at the top of the well to the drain outlet and communicating therewith.

2. A refrigerator comprising a receptacle 110 adapted to receive the produce therein, a water-tight ice-well positioned in the receptacle and spaced from the walls thereof, and a removable combined cover and ice retainer fitted in the receptacle above the well and communicating therewith, said last named member being also itself covered.

3. A refrigerator comprising a casing lined with heat-insulating material, a receptacle positioned therein and spaced from the walls thereof, a water-tight well mounted in the receptacle centrally thereof and adapted to receive ice, another ice-container removably fitted in the receptacle above the well and emptying thereinto, and means whereby a circulation of air between the ice-containers and the receptacle at various points may be had without the possibility of ice or water getting into the receptacle.

4. A refrigerator comprising a casing, a 130

lining therein spaced from the casing and adapted to receive the produce, an ice container fitted in the receptacle and arranged to hold ice so that the latter may extend for 5 the height of the produce and above the same as well, the upper walls of the ice container lying adjacent the lining and being bent inwardly and down to form a double and spaced wall, the latter being provided with holes in both thicknesses, the holes in the outer wall being lower than those in the 10 inner wall and communicating with holes in the lining, and the latter having additional holes below the upper ice container.

In testimony whereof I affix my signature.
JACK M. PUN.
